UNITED STATES PATENT OFFICE.

EDWARD MCCORKINDALE, OF HOLYOKE, MASSACHUSETTS.

LUBRICATOR.

SPECIFICATION forming part of Letters Patent No. 578,758, dated March 16, 1897.

Application filed July 20, 1896. Serial No. 599,894. (No model.)

To all whom it may concern:

Be it known that I, EDWARD MCCORKIN-
DALE, a citizen of the United States, residing
at Holyoke, in the county of Hampden and
5 State of Massachusetts, have invented certain
new and useful Improvements in Lubricators;
and I do hereby declare the following to be
a full, clear, and exact description of the
invention, such as will enable others skilled
10 in the art to which it appertains to make and
use the same.

My invention relates to lubricators for open
bearings or those which are journaled in only
one pillow-block.

15 My object is to provide a more simple and
cheap lubricator of the class described which
can be quickly and easily applied to the journal,
and one which, owing to its peculiar construction,
will be adapted to hold a large quantity
20 of oil and to evenly feed the same to the
journal, so that refilling will only become necessary
at comparatively great intervals.

Having this object in view, my invention
consists of a lubricator of novel and improved
25 construction, as will appear more fully hereinafter.

In the accompanying drawings, Figure 1 is
a front elevation; Fig. 2, an end view; Fig. 3,
30 a sectional end elevation, and Fig. 4 a longitudinal
sectional view.

The numeral 1 designates the pillow-block
of an open bearing of ordinary construction,
while 2 is the journal, which is provided with
wear-collars 3 and 4.

35 My improved lubricator is provided with
arched end pieces 5 and 6, which straddle the
journal, and each of these end pieces has feet
which are adapted to be connected to the pillow-block.

40 The numerals 8 and 9 designate strengthening
cross-bars which connect the end pieces
of the lubricator. The end pieces are cut
away to form inclined bearing-notches 10
and 11.

45 The numeral 12 designates a felt-covered
lubricating-roller which is provided with
journals 13 and 14, which are received in the bearing-notches,
and the periphery of this roller
50 so that an evenly-distributed film of oil will
be placed on the latter.

The numeral 15 designates the oil box or

receptacle, which is connected to the extreme
upper portions of the end pieces and extends
between them, said oil-receptacle being provided
with a suitable hinged top 16, having
any preferred form of catch mechanism.
There are two supply-tubes 17 and 18, whose
upper ends project up into the cover slightly
and their lower ends pass through the bottom
of the receptacle to form short spouts 19 and
20, which lie immediately over the lubricating-roller.
A wick 21 is coiled in the oil-receptacle.

The numerals 22 and 23 designate pins
which project down into the delivery-tubes,
and each of which is provided with an eye 24,
through which the wick passes, and has a
head 25, which prevents it from dropping too
far in the tube. These pins hold the ends of
the wick at or near the junction of the tube
with the bottom of the receptacle.

The operation is obvious and as follows:
The oil is drawn up by capillary attraction
through the wick and into the tubes and
drops down through them regularly onto the
lubricating-roller, which soon becomes properly
saturated, and as the journal revolves it
applies to the latter a thin and evenly-distributed
film of oil.

80 The construction of my lubricator is such
that it is adapted to hold a large supply of
oil and to properly feed the same, so that
replenishing need only be done at comparatively
great intervals, and the lubricator is
extremely economical.

Having thus described my invention, what
I claim as new, and desire to secure by Letters
Patent, is—

1. In a lubricator, the combination with a
journal, of a lubricating-roller in contact
therewith, and a lubricant-receptacle located
above the lubricating-roller and provided
with openings which allow the lubricant to
drip onto the lubricating-roller.

95 2. In a lubricator, the combination with a
journal, of a lubricating-roller, a lubricant-
receptacle, a feed-tube adapted to deliver the
lubricant onto the roller, and a wick for elevating
the lubricant into the feed-tube.

100 3. In a lubricator, the combination with a
journal, of a lubricating-roller, a lubricant-
receptacle, a feed-tube which projects up into
the lubricant-receptacle and is adapted to de-

liver the lubricant onto the roller, and a wick extending into the receptacle and the feed-tube being adapted for elevating the lubricant into the latter.

5. In a lubricator, the combination with a journal, of a lubricating-roller in contact with the journal, a lubricant-receptacle, a feed-tube projecting up into said receptacle and adapted to deliver the lubricant onto the roller, a wick having a portion located in the receptacle, and a pin projecting down into the feed-tube and to which the wick is connected.

10 5. In a lubricator, the combination with a journal, of a lubricating-roller, a lubricant-

receptacle, a feed-tube projecting up into said receptacle and adapted to deliver the lubricant onto the roller, a pin having an eye at its lower end and provided with an upper head, and a wick passing through the eye of the pin and having a portion lying in the receptacle, said pin being located in the feed-tube.

15 In testimony whereof I have signed this specification in the presence of two subscribers.

EDWARD McCORKINDALE.
